UNITED STATES PATENT OFFICE.

JOHN KACZANOWSKI, OF NEW YORK, N. Y.

PADLOCK.

Application filed April 18, 1922. Serial No. 554,851.

To all whom it may concern:

Be it known that I, JOHN KACZANOWSKI, a citizen of the United States, residing at New York, in the county of New York and 5 State of New York, have invented certain new and useful Improvements in Padlocks, of which the following is a specification.

This invention relates to locks, being adapted for embodiment in locks for trunks, 10 suit-cases or the like, or in padlocks, or key-actuated locks generally.

The invention has for an object to provide a lock which, while of simple construction, will be characterized by difficulty in picking.

15 For further comprehension of the invention, and of the objects and advantages thereof, reference will be had to the following description and accompanying drawings, and to the appended claims in which the various novel features of the invention are 20 more particularly set forth.

Fig. 1 of the drawings is a perspective view of a suit-case having my improved lock provided thereon.

25 Fig. 2 is a longitudinal sectional view through the lock, the operating parts being shown in elevation.

Fig. 3 is an enlarged fragmentary transverse section, this view being taken along 30 the line 3—3 of Fig. 2.

Fig. 4 is a detail sectional view taken on the line 4—4 of Fig. 3.

Fig. 5 is a longitudinal vertical section, partly in elevation, of the key.

35 Fig. 6 is a transverse sectional view of the key, taken on the line 6—6 of Fig. 5.

Fig. 7 is a face view of a padlock with the invention applied thereto.

My improved lock, as embodied for application in a trunk or suit-case, comprises 40 a rectangular casing 10 which may have a widened base flange 11 formed with holes 12 adapted to receive rivets whereby the lock may be secured to the desired object such as 45 the suit-case 13 to which it is shown applied in Fig. 1, the cover 13' of the suit-case being provided with a hasp 14 which the bolt of the lock engages in a well known manner.

The bolt is indicated at 16 and comprises 50 a flat bar slidably guided along the inner wall of the casing 10 by pins 17 fixed in the latter and engaging in longitudinal slots 18 in the bolt. The end of the bolt 16 which engages the hasp 14 is laterally projected to 55 one side as at 16' and bifurcated to engage in a suitable pair of openings in the hasp.

The bolt is normally urged to locking position by a bow-spring 20 connected at one end to a stud 21 in the casing 10 and bearing at its opposite end against the rear edge of the 60 lateral projection 16' on the bolt.

The bolt is retracted by means of an arm 25 fixed on a disk 26 rotatable in the casing 10, the spindle 27 on which the disk is fixed having a squared outer end adapted to be 65 engaged in a square socket in the end of the key to turn the disk. The arm 25 projects into a notch 28 in one side of bolt 16 to operate the latter, the notch being elongated sufficiently to allow the bolt to move back 70 when the hasp engages the beveled end elements 16' thereon.

The disk 26 is normally held against rotation by means of a series of slidable pins 30 projecting therefrom parallel to spindle 27 75 and guided in hollow bosses 31 on the disk, these pins 30 being pressed outwardly by coiled expansion springs such as 32 seated in the bosses and bearing on the inner ends of the pins.

These pins are of relatively differing lengths and the outer ends thereof project into a suitably formed thickened portion of the front wall element 10' of the casing and have enlarged heads 34 thereon accommodated in interior recesses 35 in the casing 80 wall 10', the pins projecting into the recesses 35 through narrow arcuate slots 36 concentric to the axis of pintle 27. Suitably formed in the wall 10' are interior arcuate 85 slot-like recesses 37 which are of equal width to, and communicate at one end with, the circular recesses 35 and register with the slots 36, forming in effect with the latter T-grooves communicating at one end with the 90 recesses 35. The recesses 35, as shown, extend axially in each direction past the ends of the recesses 37 and the heads 34 on the pins are of an axial dimension to engage in said recesses when moved axially to registry 95 therewith. The different recesses 37 are so formed in the wall 10' to be at different relative distances from the outer face of the wall and also of the disk 26. Formed in the wall 10' are circular openings 38 registering with 100 the circular recesses 35.

In opening the lock I employ the key shown in Figs. 5 and 6 and comprising the circular shank 40 with the socket 41 in its forward end adapted to engage spindle 27, 110 and having a handle enlargement 42 on its other end. Upon the shank 40 is rotatably

mounted a collar 43 having a number of pins 44 of different lengths projecting forwardly therefrom parallel to the shank 40 and spaced so as to engage in the different openings 38 in casing wall 10' when the shank engages the spindle 27 of the lock. Fixed on the shank 40 is a pin 45 projecting into an arcuate slot 46 in the inner face of the collar 43, thus allowing a limited relative rotative movement of the collar on the shank. The casing wall 10' has an opening 48 therein which registers with the spindle 27 and through which the key is inserted.

The manner of operation of my improved lock is as follows: The lengths of the different pins 44 are so proportioned with respect to the relative positioning of the arcuate recesses 37 with regard to either the face of disk 26 or of casing wall 10' that when the key is inserted in the opening 48 and the front end of the shank engages the disk 26, or the collar 43 engages the wall 10', each of the heads 34 on the spring-pressed pins 30 will be moved into registry with said arcuate recesses 37, thus permitting partial rotation of the spindle 27 and retraction of the bolt 16, the shanks of the pins 30 moving through the slots 36, and the heads through the recesses 37. When the heads ride off the key-pins 44 they will have engaged with the recesses 37, permitting their movement to be continued. When the key is withdrawn the bolt 16, under the influence of spring 20, causes the disk 26 to be rotated backward, the heads 34 on pins 30 snapping outwardly into the outer ends of the circle recesses 35 and so locking the disk. The hasp 14, when the lock is to be secured, is simply pushed into place through the usual opening in the casing wall 10'.

As indicated in Figs. 2 and 7 I may provide a dummy locking element 49 to confuse anyone trying to pick the lock. In Fig. 7 I have shown my invention applied to a padlock 50 the key receiving spindle being indicated at 27' and the openings for the pins 44 at 38'.

Having thus described my invention what I claim as new and desire to protect by Letters Patent of the United States is as follows:

1. A lock comprising a casing, a bolt, a key-engageable spindle rotatably mounted in said casing and adapted to operate said bolt, a series of spring-pressed pins spaced

around and fixed to said spindle and extending parallel thereto, said pins having heads thereon, and pairs of fixed elements in the casing spaced apart a distance, longitudinally of said pins equal to the longitudinal dimensions of said heads, and adapted to prevent rotary movement of the spindle by engaging the said heads.

2. A lock comprising a casing, a bolt, a key-engageable spindle rotatably mounted in said casing and adapted to operate said bolt, a series of spring-pressed pins spaced around and fixed to said spindle and extending parallel thereto, said pins having heads thereon, and pairs of fixed elements in the casing spaced apart a distance, longitudinally of said pins equal to the longitudinal dimensions of said heads, and adapted to prevent rotary movement of the spindle by engaging the said heads, said pins being of relatively varying lengths, for the purpose specified.

3. A lock comprising a casing, a bolt, a key-engageable spindle rotatably mounted in said casing and adapted to operate said bolt, disk fixed on said spindle and having a series of hollow bosses thereon spaced around the spindle and extending parallel thereto, spring-pressed pins guided in said bosses and held against rotation by a fixed part of the casing, the front wall of the casing having openings therein registering with the said pins when the lock-bolt is in operative position.

4. A lock comprising a casing, a bolt, a key-engageable spindle rotatably mounted in said casing and adapted to operate said bolt, a disk fixed on said spindle and having a series of hollow bosses thereon spaced around the spindle and parallel thereto, spring-pressed pins guided in said bosses and having heads thereon projecting into interior recesses in the front wall of the casing, arcuate T-grooves in the inner face of the said front wall communicating at one end with said recesses and having their transverse arms communicating with the said recesses between the ends thereof, said front wall of the casing having openings therein communicating with the said recesses.

In testimony whereof I have affixed my signature.

JOHN KACZANOWSKI.
